CLAIM

The ornamental design for a tape dispenser, as shown and described.

DESCRIPTION

FIG. 1 is a perspective view of a tape dispenser, showing our new design;

FIG. 2 is a front view thereof, the rear view being a mirror image thereof;

FIG. 3 is a top view thereof;

FIG. 4 is a bottom view thereof;

FIG. 5 is a right side view thereof;

FIG. 6 is a left side view thereof; and,

FIG. 7 is a perspective view thereof in use condition.

The broken lines shown in FIGS. 1 through 7 represent unclaimed portions of the tape dispenser and form no part of the claimed design. The roll of tape shown in broken lines in FIG. 7 represents environment and form no part of the claimed design.

1 Claim, 3 Drawing Sheets
